UNITED STATES PATENT OFFICE.

MARTIN S. HEABLER, OF McCOMB, OHIO.

WINDOW-CLEANER.

No. 853,783.

Specification of Letters Patent.

Patented May 14, 1907.

Application filed August 22, 1906. Serial No. 331,655.

To all whom it may concern:

Be it known that I, MARTIN S. HEABLER, a citizen of the United States, residing at McComb, in the county of Hancock and State of Ohio, have invented new and useful Improvements in Window-Cleaners, of which the following is a specification.

This invention relates to that class of window cleaners which are provided with a porous strip adapted to be saturated with water, or suds for the purpose of washing the window, and with an elastic strip of rubber or other suitable material for the purpose of drying the window.

5 The object of the invention is to simplify and improve the construction and operation of this class of devices and to provide an efficient and inexpensive window cleaner.

With these and other ends in view which will readily appear as the nature of the invention is better understood, the same consists essentially in a sheet metal blank formed with flanges for the purpose of holding the porous and elastic strips; the invention further consists in the formation of a window cleaner from a blank of the character set forth; the invention further consists in the improved construction and novel arrangement and combination of parts which will be hereinafter fully described and particularly pointed out in the claims.

In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

40 In the drawings: Figure 1 is a plan view of a window cleaner constructed in accordance with the principles of the invention. Fig. 2 is a transverse sectional view of the same taken on the plane indicated by the line 2—2 in Fig. 1. Fig. 3 is a transverse sectional view showing the blank from which the cleaner is formed, said view being taken on the plane indicated by the line 3—3 in Fig. 1. Fig. 4 is a longitudinal sectional view taken 45 on the line 4—4 Fig. 2.

50 Corresponding parts in the several figures are denoted by like characters of reference.

The body of the improved window washer is manufactured from a strip of sheet metal 1 of suitable dimensions, said strip being bent or crimped to form two pairs of flanges 2, 2

and 3, 3 disposed transversely of the sheet or blank parallel to each other, each of said flanges being composed of two thicknesses of metal, as will be readily understood. The 60 flanges 3, 3 are suitably spaced apart to accommodate between them a strip 4 of porous material, such as felt, although other suitable material may be employed. The flanges 2, 2 are suitably spaced apart to accommodate 65 between them a strip 5 of rubber or other suitable elastic material. The flanges 2, 2 and 3, 3 are disposed at suitable distances from the end edges of the sheet or blank so that, when the latter is bent to the cylindrical 70 shape clearly indicated in Fig. 2 of the drawings, and the projecting ends of the sheet or blank are overlapped, the flanges 2, 2 will be spaced from the flanges 3, 3 a distance varied from one quarter to one third the circumference 75 of the cylinder. When the sheet or blank is bent to form the cylindrical body, the overlapped ends 6 and 7 are secured together by means of solder, as shown at 8, or in any other suitable manner.

When the sheet of blank has been bent to form the cylindrical body A, the flanges 2, 2 and 3, 3 will extend radially from said body.

The cylindrical body A is provided with diametrically disposed apertures 9 and 10 85 which are connected by means of a slightly tapering tube 11; the latter being secured in position by means of solder or in any other suitable manner, said tube being for the reception of the pole or handle.

90 The porous strip 4 is secured in position between the flanges 3, 3 by means of transverse bolts 12 which also serve to draw said flanges together so as to prevent them from spreading. By tightening the nuts 13 on 95 the bolts 12 the flanges 3, 3 will firmly grip or clamp the porous strip 4, which latter projects a suitable distance beyond the edges of the flanges. The flexible strip 5 may be secured between the flanges 2, 2 by punching or upsetting the latter to form burs 14 which engage the elastic strip so as to prevent its withdrawal. The flanges 2, 2 are preferably reinforced upon the under side of the sheet or blank, or, which is the same thing, upon the 100 inner side of the cylindrical body by means of solder, as shown at 15, for the purpose of preventing said flanges from spreading.

105 A window cleaner constructed in accordance with the principles of this invention may be manufactured at a very moderate expense, the material employed being quite

inexpensive while the labor required in the manufacture of the device is very slight. The porous as well as the elastic strip may be readily replaced when worn.

5 In using the device, it is mounted upon a pole or handle, it is then immersed in water or other liquid until the porous strip is saturated, when it may be employed for washing a window which is afterward dried in the usual manner by means of the flexible rubber strip.

Having thus described the invention what is claimed is:

10 The herein described window cleaner made from a single sheet metal blank and comprising integral radially extending flanges; each

composed of a double thickness of the material of which the cleaner is formed, a strip of porous material secured between two of said flanges by means of clamping bolts, and a strip of flexible material secured between the other pair of flanges by means of burs formed in one of the flanges, and a tapering tube secured diametrically in the cylindrical body of the cleaner for the reception of the handle.

In testimony whereof, I affix my signature in presence of two witnesses.

MARTIN S. HEABLER.
